UNITED STATES PATENT OFFICE.

RICHARD M. BEDELL, OF BROOKLYN, NEW YORK, ASSIGNOR TO MERGENTHALER LINOTYPE COMPANY, A CORPORATION OF NEW YORK.

TYPOGRAPHICAL MACHINE.

1,098,424.

Specification of Letters Patent.

Patented June 2, 1914.

Application filed June 19, 1912. Serial No. 704,486.

To all whom it may concern:

Be it known that I, RICHARD M. BEDELL, a citizen of the United States, and a resident of Brooklyn, county of Kings, and State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started.

In the Mergenthaler patent above mentioned, the distributing devices comprise rotating screws to convey the matrices along a grooved rail or bar, from which they are released at the proper points to return them to the appropriate channels in the magazine, and my invention is herein set forth in connection with that specific mechanism. Obviously, however, the principles thereof are capable of broader application, and may be adapted to distinctly different styles of distributing devices, as well as to other forms of typographical machines, such for instance as those handling type or dies instead of matrices. Generally speaking, I desire it to be understood that I do not limit myself to any specific form or embodiment, except in so far as such limitations are specified in the claims.

A principal feature of my invention is a special means for arresting the driving mechanism in the event that the operation of the distributing devices is checked or retarded, which feature generically speaking is not novel. For instance, in the application for Letters Patent of John R. Rogers, Serial No. 687,691, filed April 1, 1912, stop devices are illustrated, wherein is employed a member formed with cam faces and a pin or stud to contact therewith, in the event of some derangement of the parts which renders it essential or desirable to arrest the distributing mechanism, such contact effect-

ing the disengagement of the driving clutch. In the said application, a single cam member is employed and it is shown specifically as formed with four cam faces, the result of this construction being the possibility of a quarter revolution of the operating means before its final arrest. In order to reduce the extent of such operation after the tripping of the stop devices, I propose to use a plurality thereof arranged in different relation to the driving mechanism, so that the latter will be checked at additional points in the cycle of operation. For this purpose, I preferably employ a plurality of cam members, mounted so that the cam faces of one are alternated or staggered in relation to those of another, and in connection with each of them a pin or stud to engage therewith. For instance, in place of the single cam member having four faces, I have illustrated two cam members each having eight faces, which as previously mentioned are relatively staggered or alternated, and it will be seen that the rotation possible after the tripping of the stop devices is thus reduced from a quarter to one-sixteenth. It will be understood, of course, that the particular arrangement referred to is shown simply by way of example, and that the principle may be extended to any extent desired, either by employing a larger number of stop devices, or by increasing the number of cam faces in each, or both.

In the accompanying drawing: Figure 1 is a transverse section through the operating means for the distributing mechanism, having my invention applied thereto; and Fig. 2 is a front view of the same, partly broken away and partly in section.

The distributor screw A is rotated in the customary manner from a chain of gearing, comprising the gear B immediately connected to the screw, which chain receives its motion from the band wheel C, sleeve D, sprocket gearing E, E¹, etc. The specific arrangement of gearing is unessential to the present invention, and is or may be of any desired form, such for instance as illustrated in the Rogers application previously referred to. The gear B is mounted upon the screw A in such manner as to be capable of a partial rotation thereon, this being secured in the form shown by the engagement of the pin A¹ on the screw in the inclined slot B¹ in the hub of the gear. The gear B is nor-

mally pressed outwardly or toward the left by the projection F^1 on the lever F , pivoted at F^2 to the machine frame and forced outwardly by the spring F^3 connected to the 5 opposite end thereof. It is this spring pressure that holds the gear B in its normal relation to the screw A , namely, with the pin A^1 at the lower end of the inclined slot B^1 , the strength of the spring being sufficient to 10 maintain the relation in ordinary operation. When, however, the rotation of the screw is checked or retarded, as for instance by the engagement therewith of an arrested matrix, the gear B continues to rotate with respect 15 to the screw, the effect of this relative movement being also to shift the gear laterally or inwardly thereon, due to the outward travel of the pin A^1 in the inclined slot B^1 .

The sleeve D is provided with the friction 20 clutch surface D^1 , which is normally held in engagement with the wheel C by the pressure of the spring D^2 . The arrest of the driving means is effected by the movement of the sleeve D in the opposite direction 25 against the force of the spring D^2 , thereby interrupting the frictional engagement referred to. The lateral movement of the gear B previously described is availed of to effect this disconnection.

30 The sleeve D carries two cam members K , K , formed with laterally inclined faces K^1 , K^1 , and in connection with each of these members I provide a pivoted stop arm J , carrying a stud or pin L located in position 35 to be projected into the path of a cam face K^1 . In the drawing, the parts are shown in normal or operative position, namely, with the abutments H , H , of the stop arms J , J , resting upon the flanges G^1 , G^1 , of the projection G connected to the upper end of the 40 lever F . In this relation, the spring F^3 holds not only the flanges G^1 , G^1 under the abutments H , H , and consequently the pins or studs L out of the path of the cam members K , K , but also the gear B in its outward and active relation to the screw A . If 45 for any reason the rotation of the screw A be arrested or retarded, the continued rotation of the gear B moves it laterally in the manner previously described, and because 50 of its engagement with the projection F^1 on the lever F , the latter is turned about its pivot F^2 and against the force of the spring F^3 , thereby removing the flanges 55 G^1 , G^1 from their operative position beneath the abutments H , H . The stop arms J , J are thus tripped and their pins L , L projected into the paths of the cam faces K^1 , K^1 .

In many respects the operation so far described is substantially similar to that of the mechanism old in the art. However, it will be noted that two cam members K , K , and coöperating stop arms J , J are employed, and that the cam faces K^1 of one 65 set are staggered or alternated with relation

to those of the other set, the practical effect of which arrangement is to double the number of points at which the mechanism may be arrested. This duplication of the cam members is of particular importance and advantage, in view of the fact that it gives a materially larger number of stopping points than may be conveniently provided for on a single member, it being noted in this connection that such number is somewhat limited in view of the necessary extent and slope of the cam faces thereon.

Having thus described my invention, its construction and mode of operation, what I claim and desire to secure by Letters Patent of the United States is as follows:

1. In a typographical machine, the combination of distributing mechanism, rotary actuating means therefor, and a plurality of independent stop devices, the several stop devices being so arranged that one will arrest the actuating means at different points in their rotation and another at intermediate points.

2. In a typographical machine, the combination of distributing mechanism, actuating means therefor, and a plurality of independent stop devices, each adapted to arrest the actuating means at a plurality of points, the several stop devices being disposed in different relation to the actuating means so as to arrest the latter at correspondingly different points.

3. In a typographical machine, the combination of distributing mechanism, actuating means therefor, and a plurality of independent stop devices, the several stop devices each comprising a plurality of effective elements arranged in the respective devices in alternated or staggered relation to each other, so as to arrest the actuating means at different points.

4. In a typographical machine, the combination of distributing mechanism, actuating means therefor, and a plurality of stop devices, each of said stop devices comprising a member formed with a plurality of cam faces and a part to engage therewith, the said cam faces in the several members being disposed in alternated relation to each other, so as to arrest the actuating means at different points.

5. In a typographical machine, the combination of distributing mechanism, actuating means therefor, and a plurality of stop devices, each comprising a member K formed with a plurality of cam faces K^1 and a part L to engage therewith, the said cam faces K^1 in the different devices being respectively alternated, to arrest the actuating means at different points.

6. In a typographical machine, the combination of distributing mechanism, actuating means therefor comprising a rotary driving part and a rotary driven part, and

a plurality of stop devices carried by the driven part and each adapted to disengage the same from the driving part at a plurality of points in its rotation, the several stop devices being arranged so as to act at different points with relation to each other.

5 In testimony whereof I hereunto set my

hand this fourteenth day of June, 1912, in the presence of two attesting witnesses.
